UNITED STATES PATENT OFFICE

158,629

COMBINATION TOOL

Paul Weynand, San Antonio, Tex.

Application April 29, 1949, Serial No. 2,333

Term of patent 14 years

(Cl. D54—13)

To all whom it may concern:

Be it known that I, Paul Weynand, a citizen of the United States of America, residing at San Antonio, in the county of Bexar and State of Texas, have invented a new, original, and ornamental Design for Combination Tools, of which the following is a specification, reference being had to the accompanying drawing, forming part thereof.

Fig. 1 is a side elevational view of a combination tool, showing my new design.

Fig. 2 is a front elevational view; and

Fig. 3 is a rear elevational view.

I claim:

The ornamental design for a combination tool, as shown.

PAUL WEYNAND.
